UNITED STATES PATENT OFFICE

127,615

DESIGN FOR A BLANKET OR SIMILAR ARTICLE

Frederick Heppner Buchholz, New York, N. Y.,
assignor to The Esmond Mills, Inc., New York,
N. Y., a corporation of Rhode Island

Application May 2, 1941, Serial No. 100,745

Term of patent 7 years

To all whom it may concern:

Be it known that Frederick Heppner Buchholz, a citizen of the United States of America, residing at 19 Bethune Street, in the Borough of Manhattan, city, county, and State of New York, has invented a new, original, and ornamental Design for a Blanket or Similar Article, of which the following is a specification, reference being had to the accompanying drawing, forming a part thereof.

The figure is a face view of a blanket showing my new design.

I claim:

The ornamental design for a blanket or similar article, substantially as shown.

FREDERICK HEPPNER BUCHHOLZ.
